D12-18. OR D 7,445 EX

DESIGN.

C. M. MURCH.

Omnibuses.

No. 7,445.

Patented May 19, 1874.

C. M. MURCH.

Design for an Omnibus.

FIG. 1.

FIG. 1.

FIG. 2.

UNITED STATES PATENT OFFICE.

CHAUNCEY M. MURCH, OF CINCINNATI, OHIO.

DESIGN FOR OMNIBUSES.

Specification forming part of Design No. 7,445, dated May 19, 1874; application filed April 9, 1874.
[Term of Patent 14 years.]

To all whom it may concern:

Be it known that I, CHAUNCEY M. MURCH, of Cincinnati, Hamilton county, Ohio, have invented or produced a new Design for Omnibuses, of which the following is a specification:

In the accompanying drawings, Figures 1 and 2 are, respectively, a side elevation and longitudinal section, and Fig. 3 is a section at the line $x x$, of an omnibus embodying my design.

The body consists of a central octagonal space, A, with rectangular projections B and S. Projecting from the front of the body is an open frame or bracket, N.

I claim as new and of my invention—

1. The design of the body, consisting essen-

tially of an octagonal central part, A, and narrower rear and front parts B and S, of approximately rectangular form.

2. The design of the bracket N, consisting essentially of bars connected in triangular form with a circular center-piece, substantially as shown.

3. The design for an omnibus, consisting of the body, front frame, and wheel-guards, as represented.

In testimony of which invention I hereunto set my hand.

CHAUNCEY M. MURCH.

Attest:

GEO. H. KNIGHT,
OCTAVIUS KNIGHT.
